UNITED STATES PATENT OFFICE

135,950

DESIGN FOR A TRIPLE HANDLE CONTROLLER

Erwin J. Panish, Bridgeport, Conn.

Application April 28, 1943, Serial No. 110,065

Term of patent 14 years

To all whom it may concern:

Be it known that I, Erwin J. Panish, a citizen of the United States, residing at Bridgeport, in the county of Fairfield and State of Connecticut, have invented a new, original, and ornamental Design for a Triple Handle Controller, of which the following is a specification, reference being had to the accompanying drawing, forming part thereof.

Figure 1 is a perspective view of the triple handle controller showing my new design.

Fig. 2 is a front view thereof.

Fig. 3 is a side view thereof.

I claim:

The ornamental design for a triple handle controller, as shown.

ERWIN J. PANISH.
